UNITED STATES PATENT OFFICE.

THOMAS OLINGER, OF HOLLAND, MICHIGAN, ASSIGNOR TO FEDERAL MANUFACTURING COMPANY, OF HOLLAND, MICHIGAN, A CORPORATION OF MICHIGAN.

FLUE-DRAFT DOOR.

Application filed July 11, 1927. Serial No. 204,762.

This invention relates to a draft door construction particularly designed for use as a check draft on the smoke pipes of furnaces, stoves and the like. It is a primary object and purpose of the present invention to provide a very simple and economically constructed draft door and mounting therefor which may be applied to smoke pipes whether in horizontal or vertical position, 10 the door being capable of ready application to the part on which it is mounted for pivotal movement at different points so that the door may be swung about a horizontal axis whether mounted on a vertical or a horizontal smoke pipe. The invention consists in novel constructions and arrangements and combinations of parts for simply, effectively and economically attaining the ends stated.

An understanding of the construction of 20 a preferred embodiment of the invention may be had from the following description taken in connection with the accompanying drawing, in which,

Fig. 1 is a fragmentary elevation illustrating the draft door applied to a horizontally located smoke pipe.

Fig. 2 is a similar view showing the same applied to a vertical pipe.

Fig. 3 is a perspective view of the supporting fixture for the draft door and which is 30 permanently mounted on the smoke pipe.

Fig. 4 is a perspective view of the pivotally mounted draft door with the interposed connecting bracket therefor which is adjustably mounted on the fixture shown in Fig. 3 at different positions thereof, and

Fig. 5 is a fragmentary vertical section through the upper part of the draft door construction showing the pivotal mounting of said door and the manner in which it is connected with the supporting fixture therefor.

Like reference characters refer to like parts in the different figures of the drawing. 45 In the construction shown, a supporting fixture, on which the draft door is to be mounted, is provided designed for attachment to a furnace or stove smoke pipe. The fixture comprises a circular flange or ring 1 of sheet metal shaped to fit the curvature of the pipe on which it is placed. A cylindrical member 2 extends from the ring 1 and at its free end is formed with an inwardly bent annular lip 3. The cylinder 2 has two spaced apart openings 4 cut therein at one

side and, in addition has another pair of openings 5 like the openings 4 cut therethrough substantially at right angles to the openings 4. It is of course evident that other pairs of openings may be made in the 60 cylinder 2 at any desired points.

The draft door 6 is made from a plate of sheet metal and is of substantially circular form and has an annular inturned lip or flange 7 around it to fit over the lip 3 on the 65 cylindrical member 2. The door 6 at one side is equipped with two spaced apart upwardly extending ears 8 of the form shown.

A bracket made from a single piece of sheet metal is provided, including a flange 9 70 curved to fit against a side of the cylindrical member 2 and at each end is formed with a downwardly extending ear 10. The distance between the ears 10 is such that the same may pass freely through either of the 75 pairs of openings 4 or 5. A flange 11 is bent upwardly substantially at right angles to the somewhat curved flange 9, in which two spaced apart openings 12 are made and through which the ears 8 of the draft door 6 80 may pass for pivotally mounting the door on the bracket.

When the supporting fixture shown in Fig. 3 is attached to a horizontally located pipe, as 13 in Fig. 1, the pairs of openings 4 lie at the upper side of the cylindrical member 2 and the bracket described may be attached by inserting ears 10 through the openings 4, clinching the same after passing through said openings as shown in Fig. 90 5. When the fixture is attached to a vertical pipe, as 14 in Fig. 2, the other pair of openings 5 in the cylindrical member 2, are at the upper side of member 2 and the bracket may be attached by inserting the ears 10 95 through said openings. It is evident that irrespective of whether the smoke pipe is horizontal or vertical, a pair of openings 4 or 5 in the part 2 will be located at the upper side thereof and that the door may be attached so that it will swing about a horizontal axis so that it may be opened or closed by means of the usual draft chain, indicated at 15.

The invention described is very practical 105 and is universal in its application to smoke pipes of furnaces, stoves or the like, being applicable to such pipes whether in vertical or horizontal position. The construction is very economical to make and may be made 110

in large quantity production at very low cost. Many variations in minor detail of structure may be resorted to without departing in any way from the invention which is defined in the appended claims, the invention comprehending all forms of structures coming within the scope of said claims.

I claim:

- 5 1. A device of the class described comprising, a supporting fixture having a flange shaped to fit against a cylindrical smoke pipe and a cylindrical member extending from said flange having an open outer end, said cylindrical member having a plurality 10 of openings through the sides thereof, a bracket, means for attaching said bracket to said cylindrical member at a plurality of different positions defined by said openings therethrough, and a draft door pivotally 15 mounted on said bracket.
- 10 2. A device of the class described, comprising, a supporting fixture having a flange shaped to fit against the outer side of a smoke pipe and including a cylindrical 15 member extending from said flange having an open outer end, said member having a plurality 20 of openings through the sides thereof, a bracket formed with a flange to fit against the outer side of said cylindrical member, ears on the bracket to extend through any pair of said openings in said cylindrical member and a draft door pivotally mounted on said bracket and shaped to close the outer end of the cylindrical member.

25 plurality of pairs of openings therethrough, a bracket formed with a flange to fit against the outer side of said cylindrical member and with ears at the end thereof to extend through the openings of any pair of said openings and a second flange at right angles to the first flange, and a draft door pivotally mounted on the second flange and shaped to close the outer end of the cylindrical member.

30 3. A device of the class described comprising, a supporting fixture having a flange shaped to fit against the outer side of a smoke pipe and including a cylindrical 35 member extending from said flange having an open outer end, said member having a plurality of pairs of openings therethrough, a bracket formed with a flange to fit against the outer side of said cylindrical member, ears on the bracket to extend through any pair of said openings in said cylindrical member and a draft door pivotally mounted on said bracket and shaped to close the outer end of the cylindrical member.

40 45 In testimony whereof I affix my signature.
50 THOMAS OLINGER.
